Application August 14, 1941, Serial No. 406,918

22 Claims.

(Cl. 161—23)

The present invention relates to timing apparatus, and more particularly to interval timers which can be set to actuate a signal device or to perform some other control function at a pre-selected time or upon the lapse of a predetermined time interval. One typical embodiment of my invention is represented by a domestic or kitchen type of interval timer which the housewife is adapted to set so as to sound a signal upon the lapse of a preselected time interval, such signal serving to remind her that a particular cooking operation or other culinary operation is completed. This type of interval timer is usually driven by a continuously running clock motor, such as an alternating current synchronous motor, which constitutes the time driven means for the timer. Frequently, such an interval timer is also a part of an automatic timing apparatus associated with an electric cooking range or the like for automatically controlling the starting and stopping of a cooking operation.

The invention is concerned primarily with providing improved means for minimizing or avoiding the drag load which most of these interval timers impose upon the alternating current synchronous motor and the time train/driven therefrom. The majority of the interval timers of the prior art utilize a friction clutch to transmit the driving torque from the time driven means to the manually settable device which determines the length of the desired time interval. This friction clutch affords a slippage connection which enables the manually settable device to be turned back counter to the rotation of the time driven means when setting up the desired time interval. It also affords a slippage connection which enables the manually settable device to stop rotation in a predetermined normal position after signalling the lapse of the preselected time interval, without stopping the continuous operation of the electric motor or other time driven means. In the months or years of continuous operation of the electric motor, the friction clutch is undergoing a slipping operation practically all of the time. This imposes a continuous drag load on the electric motor and on the time train of reduction gearing extending from the motor to the friction clutch. Such continuous drag load causes increased current consumption by the electric motor, and also results in a more rapid wear of the motor and of the time train gearing. Furthermore, such continuous slippage also results in substantial wear of the friction clutch, impairing its life and the adjustment of the spring load imposed thereon.

My improved construction avoids each of the foregoing objections and limitations present in these prior friction clutch arrangements.

My improved construction serves to free the time actuated driving element from substantially all torque or friction drag during the normal condition of the apparatus when the manually settable element is not being driven.

Different preferred embodiments of my invention are illustrated in the accompanying drawings in which:

Figure 1 is a fragmentary front view of an electric clock embodying my improved timing apparatus, different portions being broken away at different levels to illustrate various details of the construction;

Figure 2 is a fragmentary perspective view showing the driving relation between the time actuated driving element and the manually settable interval timer;

Figure 3 is a fragmentary axial sectional view taken approximately on the plane of the line 3—3 of Figure 2;

Figure 4 is a similar sectional view showing the driving and driven elements in their free-wheeling or idling relation;

Figure 5 is a side view and Figures 6 and 7 are fragmentary front elevational views showing one preferred embodiment of gong striking mechanism adapted to be actuated by the interval timer;

Figure 8 is a similar view on a large scale showing a circuit controlling switch arranged to be actuated by the interval timer;

Figure 9 is a fragmentary view illustrating another arrangement of circuit controlling switch adapted to be actuated by the mechanism illustrated in Figures 5 and 6.

Figure 10 is a transverse sectional view taken approximately on the plane of the line 10—10 of Figure 9, and showing a typical switch and buzzer.

Figure 1 illustrates the left hand portion of a typical electrical timing apparatus for electric ranges and the like. This general form of electrical timing apparatus is disclosed in the prior patent of myself and Mr. Alfred W. Gardes, No. 2,302,625, issued November 17, 1942, and in my prior Patent No. 2,301,942, issued November 17, 1942. A housing 21 has a large central opening therein through which appears the dial 22 of the electric clock, this dial having the usual hour and fractional hour markings 23, and the hour and minute hands 24 and 25 respectively. A resetting knob 26 extends forwardly from the front

side of the cover glass 21, this knob being operative to reset the hands of the clock if the clock motor should stop by reason of current failure or any other cause.

Concentric with the clock dial are the two rotatable adjusting members 28 and 29 which are settable to different positions to predetermine the starting and stopping of the cooking operation. The adjustable member 28 is preferably in the form of a continuous ring surrounding the clock dial and bearing the notation "Stop cooking." The ring is formed with an outwardly projecting actuating knob 28', preferably located adjacent to the above notation. Extending inwardly from the ring in registration with this knob is a pointer formation 28'' which is adapted to register with the hour and fractional hour markings 23 on the clock dial in the different angular positions to which the adjusting ring is moved. The other adjusting member 29 may likewise be in the form of a continuous ring, surrounding the ring 28, although in the preferred construction the member 29 is in the form of an arm having a knob or handle extremity 29' which is of substantially the same size and shape as the knob 28' on the ring 28. An inwardly extending pointed formation 29'' on the adjustable member 29 overlies a portion of the adjusting ring 28, and is adapted to register with a second series of hour and fractional hour markings 31 provided on the adjusting ring 28. These latter marks designate the "Cooking hours" i. e. the length of time that the cooking operation is to continue, the adjusting member 29 being movable to different ones of these marks for adjusting the length of the cooking time period. The manner in which these two adjusting members 28 and 29 are set, and the particular mechanism through which these settings automatically control the starting and stopping of a cooking operation, are clearly set forth in the aforementioned copending applications identified above, and hence there is no need of duplicating that portion of the disclosure here.

The electric clock and other time driven elements of the apparatus are driven by the electric motor 61 (Figure 9) which, in almost all instances, will be a synchronous alternating current motor of any preferred construction, such as are commonly employed in electric clocks and the like. The interval timer constituting the present invention is illustrated as being disposed to the left of the clock 22 (Figure 1), and is arranged to be driven from the time train of the electric motor and electric clock through a large gear 171 which meshes with pinion 172 rotatably mounted on a suitable supporting shaft 173. As shown in Figure 3, the upper end of said shaft 173 is supported in a frame plate 174, and below the pinion 172 the shaft is supported in a frame plate 49. Rotating with the pinion 172 is a time driven frictional driving wheel 175. This driving wheel has a wedge-shaped periphery which is adapted to effect peripheral driving engagement with a cooperating frictional driven wheel 177. The latter is mounted on a spindle 178 which carries a manually rotatable knob 44 through which different time settings can be given to the driven wheel 177. The knob 44 is mounted on the spindle 178 exteriorly of the casing 21, and has a flanged inner portion which is marked with minute graduations 44', ranging say from 0 to 60. These marks are adapted to be brought into registration with an index pointer 45 on the casing 21 when it is desired that

the interval timer shall sound an audible alarm upon the lapse of a selected time interval. Rigidly anchored to the lower portion of the spindle 178, so as to rotate directly with the setting knob 44, is a time settable tripping arm 183. A hub 184 secured to the arm 183 has a drive fit over the splined portion of the spindle 178. Rotary motion is transmitted from the large frictional drive wheel 177 to the time settable arm 183 through the instrumentality of a drive stud 186. This stud is rigidly anchored to the arm 183 and projects forwardly therefrom through apertures 187 formed in the friction wheel 177. The apertures 187 are elongated radially of the wheel or made sufficiently larger than the drive stud 186 that the friction wheel is capable of axial shifting movement relatively to the stud, and is also capable of a limited amount of wobble motion relatively to the stud.

The friction wheel 177 is composed of two thin cup-shaped washers or disks 181 preferably composed of spring tempered stainless steel. The two disks are duplicates, each comprising a cupped central portion 182 and a flat peripheral flange portion 183. The opposing cupped portions 182 of the two disks are staked over a hub 187. Also secured to said hub, over the outer sides of the diaphragms, are washers or backing disks 188. The hub 187 is capable of sliding axially along the spindle 178, and is also capable of a slight wobble motion relatively thereto, in order to accommodate the freedom of movement referred to in connection with the driving stud 186 and driving slots 187.

The peripheral flanges 183 of the two disks or diaphragms are normally held pressed together under substantial resilient pressure. The frictional driving pinion 175 transmits a drive peripherally to the friction driven wheel 177 by spreading the peripheral flanges 183, 183 apart and establishing a frictional grip with the driven wheel between these flanges, as clearly shown in Figure 3. The beveled periphery of the driving pinion 175 functions in the manner of a rolling wedge for spreading the flanges 183, 183 apart in the progressive rotary motion of the driven wheel. It will be understood that there is a flexure of each disk substantially at the point of frictional engagement, so that the two disks are not bodily separated from each other but only a limited area of the material in each disk is rolled or flexed away from the other disk in the general region of the driving pinion 175. This establishes line contact between these two friction wheels at the opposite shoulders 201 of the beveled pinion. These two lines or circles of contact insure an accurate, closely maintained pitch ratio between the driving wheel and the driven wheel so that there is no objectionable variation in the gear ratios between these two wheels in the manufacture and operation of the device.

Formed at one point in the periphery of the large friction wheel 177 is a clearance pocket 184 where the driving pinion 175 loses frictional driving engagement with the large wheel, resulting in the driving pinion rotating idly within the clearance pocket without imparting rotary motion to the large wheel. This clearance pocket is formed by punching outwardly projecting humps or indentations 185 in the flange portions 183 of the two disks 181, and arranging these humps in oppositely facing relation to form the clearance pocket. Figure 4 illustrates the position of the parts when the clearance pocket 184

has revolved around into registration with the small driving wheel 175, this being the normal position of the parts, at which time the driving wheel rotates idly in the clearance pocket without imparting rotary motion to the large wheel 177. However, as soon as the large wheel 177 is rotated through a manual setting operation performed by turning the knob 44, the frictional driving relation is reestablished between the small friction wheel 175 and the large friction wheel 177, so that the small wheel begins to drive the large wheel back in the reverse direction for restoring the large wheel to its original position, i. e., with the clearance pocket 194 registering with the small wheel 175. The driving ratio between the small wheel and the large wheel is such that the large wheel is rotated through one complete revolution in substantially 60 minutes, corresponding to the markings 44' on the knob 44.

The tripping arm 183 which rotates concurrently with the knob 44 and friction wheel 177 may be arranged to trip a striking hammer for sounding a gong, or it may be arranged to close switch contacts for energizing a buzzer, or it may be arranged to perform other signal functions. In the embodiment illustrated in Figures 5 and 6 this tripping arm is arranged to trip a striking hammer for sounding a gong. In this embodiment, the outer end of the arm 183 carries a pin 203 on which are mounted a large roller 204 and a smaller roller 205. The large roller is adapted to cock a striking hammer 207 to cocked position in the operation of manually setting the device for signalling the lapse of a predetermined time interval, and the small roller 205 is adapted to trip a retaining latch 208 which releases the gong hammer 207 at the lapse of the predetermined time interval. The striking hammer 207 is adapted to strike a gong 209 which is shown as surrounding the electric motor 61, such arrangement enabling a more compact construction to be obtained. The gong hammer 207 is carried on one end of a flexible reed or leaf spring 210 which has its other end secured to a rocking plate 211. This plate, together with a companion plate 212 spaced laterally therefrom, form a rocking frame which is mounted for rocking movement on the rearwardly projecting portion of the shaft 173. A spacing post 213 has its ends riveted to the plates 211 and 212 for joining said plates into a rigid frame. A tension spring 214 has one end hooked to a frame post 215 and has its other end hooked to an apertured arm 216 extending from the plate 211, this spring tending constantly to rock the frame 211-212 in a direction to swing the hammer 207 against the gong 209. A stop lug 217 projecting rearwardly from the plate 212 is adapted to strike a stationary stop shoulder 218 on the supporting frame at an instant just before the hammer 207 strikes the gong 209, whereby the actual striking of the gong occurs by spring flexure of the leaf spring 210 when the stop shoulders 217, 218 come into engagement. The rocker frame plate 212 is formed with a laterally and downwardly bent arm 221, at the extremity of which is formed a cam slope 222 ending in a raised cam dwell 223. The roller 204 on the manually settable tripping arm 183 is adapted to roll under the cam hump 223 for 70 swinging the hammer carrying frame 211, 212 upwardly to a latched position, as shown in Figure 7. Upon the tripping of this hammer carrying frame from said latched position, the hammer is swung downwardly to strike the gong 209. 75

The latch 208 performs the above function of latching the hammer carrying frame in the raised position illustrated in Figure 6. This latch 208 is mounted to oscillate around the axis of the shaft 173, concentrically with the large friction driven wheel 177. An arm 225 extending downwardly from the latch has a tension spring 226 hooked thereto, the action of this spring tending constantly to urge the latch in a counterclockwise direction, as viewed in Figure 6. A shoulder 228 on the latch is adapted to snap under the arm 221 of the hammer frame when the hammer frame has been raised to cocked position by the action of the roller 204 passing under the cam hump 223. A finger 229 projecting upwardly from the rear end of the shoulder 228 is adapted to strike the edge of the arm 221 for limiting the swinging movement of the latch 208 when the shoulder 228 assumes its latching position under the arm 221. A circular recess 231 in the forward edge of the latch 208 is adapted to be engaged by the small roller 205 on the tripping arm 183 when this tripping arm has been time-driven back to its zero or normal position. Such engagement of the small roller against the circular recess serves to oscillate the latch 208 in a clockwise direction, thereby withdrawing the latch shoulder 228 from the arm 221 and permitting the hammer frame and hammer to snap downwardly for sounding the gong.

Referring to the operation of this embodiment, the normal position of the parts is illustrated in Figure 1. The knob 44 normally stands with the 0 marking 44' in registry with the index pointer 45, thus showing that the interval timer is in a normal, non-set condition. At this time, the tripping arm 183 with its rollers 204 and 205 occupies a position which holds the small roller 205 pressed into the circular recess 231 of the latch 208, with the latch pressed to an extreme right hand position abutting against the hub 172' joining gear 172 and friction wheel 175 (Figure 1). Such abutment of the pawl finger 229 against the hub 172' establishes a limiting stop which determines when the knob 44 is in its normal or 0 position. In this position of the knob and of the tripping arm 183, the clearance gap 194 in the large friction wheel 177 is in direct registration with the small friction wheel 175. Thus, there is no appreciable friction contact between the peripheries of these two wheels. The small driving wheel 175 revolves idly or in a free-wheeling relation to the stationary large wheel, so that friction load or torque drag is imposed on the driving wheel 175 in the normal position of the interval timer. Assume now that the housewife desires to set up the interval timer for sounding the lapse of an interval of say twenty minutes. She revolves the knob 44 in a counterclockwise direction to bring the 20 marking on the knob into registration with the index pointer 45. This rotates the knob 44, large friction wheel 177 and tripping arm 183 concurrently through approximately one-third of a revolution. As the tripping arm starts this movement toward the left, the latch pawl 208 swings directly therewith under the action of spring 226, until the forward edge of the pawl comes up against the arm 221 of hammer supporting member 212, as shown in Figure 6. Swinging motion of the latch is now stopped, but the tripping arm 183 continues in its movement to the left, bringing the large roller 204 against the cam hump 223 and resulting in the hammer supporting member 212 being raised to drop the arm 221

down over the latch shoulder 228 in the operation of latching the hammer carrying member in its cocked position, as shown in Figure 7. In setting the device for a twenty minute interval, the tripping arm 183 is carried beyond the cam hump 223 down to approximately the dotted line position shown in Figure 7.

This setting rotation of the parts also interrupted the free-wheeling relation between the friction wheels 175, 177 by revolving the clearance gap 194 in a counterclockwise direction away from the driving wheel 175. In such rotation the peripheral flanges 193 of the large friction wheel are yieldingly spread apart with a progressive rolling motion which maintains both peripheral flanges pressed with a tight frictional pressure against the circles of contact 201 on the driving wheel 172. This setting motion is counter to the direction of driving influence of the driving wheel 175, the latter tending to rotate the driven wheel 177 in a clockwise direction, as indicated by the arrows in Figure 1. Hence, as soon as the counterclockwise setting motion has been stopped at the 20 minute marking, the driving action of the wheel 175 immediately starts rotating the large friction wheel in a reverse or clockwise direction for slowly rotating the parts back to their normal position. Shortly before the lapse of the 20 minute interval, the small roller 205 moves into engagement with the circular recess 281 in the latch 208, thereby swinging this latch to its releasing position (Figure 6) at the lapse of the 20 minute interval. It will be evident that a relatively close degree of accuracy can be obtained with respect to the time that the latch shoulder 228 releases the arm 221 of the hammer carrying member. Upon this tripping of the latch, the gong 209 is sounded for indicating the end of the twenty minute interval. The friction wheel 177 continues to revolve through a short additional distance for bringing the clearance pocket 194 into registration with the driving friction wheel 175, thereby interrupting the peripheral driving engagement between these two wheels. This small additional motion also carries the finger 229 of latch 208 back against the hub 172 of gear 172 for establishing a limiting stop in such direction of motion.

The ability of the driven friction wheel 177 to shift axially and to wobble slightly, as a result of its floating mounting and the loose fit between the pin 186 and slots 187, enables this driven wheel to adapt itself to any inaccuracies of assembly or motion of the parts, and to maintain the proper free-wheeling relation and the proper clutching relation without any binding or abnormal wear of the two friction wheels or their mountings.

Figure 8 illustrates a modified construction in which the manually settable tripping arm 183 is arranged to actuate electrical contact apparatus for controlling an electrically energized signal or other electric circuit. In this embodiment the construction is the same as that described above except that the end of the spring arm 210 carries movable contacts 234 and 235 instead of the clapper or hammer 207. Contact 234 is adapted to cooperate with stationary contact 234', and contact 235 is adapted to cooperate with stationary contact 235'. The circuit through contacts 234, 234' would only be closed when the rocker frame 211, 212 was maintained in the raised position illustrated in Figure 7. Where such a circuit is intended to give audible sounding upon the lapse

of a selected time interval, the circuit could be arranged to energize a solenoid operated bell striker which would drop and sound the bell upon the opening of contacts 234, 234' at the lapse of the selected time interval. The other contacts 235, 235' may be adjusted for effecting a momentary closure only at the instant that the rocker frame snaps inwardly to the position shown in Figure 6 (corresponding to the inertia impulse of the hammer 207 striking the gong 209), or they may be adjusted for maintaining continuous closure during the entire time that the rocker frame occupies its normal position (Figure 6). In the first instance, the momentary closure of the contacts may be arranged to energize a single-stroke bell. In the latter instance, the contacts may be arranged to govern a relay or perform any desired signaling or control function.

Figures 9 and 10 illustrate another modified embodiment using a different form of signal control mechanism. The driving relation to the manually settable tripping arm 183 is identical with that described in connection with the first embodiment, but the tripping arm has a pointed extremity 238 instead of carrying the rollers 204, 205. This pointed extremity is arranged to actuate a simplified form of signal operating mechanism. Such latter mechanism is substantially identical with that disclosed in the aforementioned prior patent of myself and Alfred W. Gardes, No. 2,302,625. Said operating mechanism comprises an operating lever 241 which is pivoted on a pin 242 extending upwardly from the frame plate 48, this lever member being yieldingly held in the normal position illustrated by a tension spring 243 which has one end hooked to an apertured arm 244 extending from said lever, and which has its other end hooked to a lug 245 projecting up from the plate 48. The pointed extremity of the time settable tripping arm 183 is adapted to cooperate with a corresponding wedge-shaped formation 246 on the operating lever 241, this occurring just before the settable arm 183 arrives back in its normal position in engagement with the lug or strop 245 projecting outwardly from the frame plate 48. When the time settable arm is restored to this normal position the clearance pocket 194 is in registration with the driving friction wheel 175, as previously described. The outwardly extending arm of the operating lever 241 carries a projecting roller 251 composed of insulating material. This roller is adapted to actuate a snap switch 252, best shown in Figure 10. The switch is mounted on an insulating base 253, and comprises a stationary contact 254 and movable contact 255 adapted to snap into and out of engagement with the stationary contact. This switch may be of special construction for securing a snap action between the contacts, but the details thereof are fully described in the aforementioned prior patent and need not be repeated here.

The snap switch 252 controls the circuit of a signal buzzer 261 which is shown as comprising a core 262 and a winding 263 mounted thereon, this core and winding constituting the movable element of the buzzer. The core is composed of a magnetic metal, and formed in the lower end thereof is a guide bore 264 which has a sliding fit over a stud 265 projecting laterally from the frame plate 48. The stud 265 is preferably composed of brass or other non-magnetic metal. The frame plate 48 is composed of a magnetic metal so that when the core 262 is energized it tends to move axially toward the plate 48. A compression

spring 266 interposed between the inner end of the stud 265 and the end of the bore 264 normally holds the core and winding in a retracted position as shown. The other end of the core 262 is formed with a guide pin 268 which has a slideable fit in a guide bore 269 formed in an adjustable guide screw 271. Said screw threads through a tapped hole in the upper frame plate 47 and is adapted to be locked in any vertical position of adjustment by a lock nut 273. The screw 271 is preferably composed of brass or other non-magnetic metal. The pressure of the spring 266 normally holds the shouldered end of the core against the adjacent end of the guide screw. It will be understood that the winding 263 is energized by the alternating current which operates the synchronous electric motor 61. Hence, the movable buzzer unit 262-263 tends to vibrate with the same frequency as the alternating current.

In this latter embodiment, when the tripping arm 183 arrives in proximity to the stop 248 the wedge-shaped outer end 283 of said arm engages the wedge-shaped formation 246 on the lever 241, thereby rocking said lever in a counter-clockwise direction with the continuous motion of the tripping arm 183. Such rocking movement of the lever 241 operates through the insulating roller 251 to close the snap switch 252, as described above. The snap switch is only held in its closed position for a brief time, say from 10 to 30 seconds or so, because of the small area of contact between the wedge-shaped end 283 of the arm 183 and the wedge-shaped formation 246 on the lever 241, and also because of the adjusted position of the snap switch 252 relatively to the path of travel of the roller 251. During this closed condition of the snap switch, the buzzer device 261 sounds its signal by a continuous vibration. When the wedge-shaped outer end of the tripping arm 183 slips past the wedge-shaped portion 246 of the lever 241, the lever 241 is immediately restored to normal position, and the tripping arm 183 is thereafter brought to a stop against the shoulder 248 with the clearance gap 194 of the driven wheel 177 registering with the driving wheel 175. The general construction and operation of the signal and signal operating means illustrated in Figures 9 and 10 are described in greater detail in the aforementioned prior Patent No. 2,302,625.

While I have illustrated and described what I regard to be the preferred embodiments of my invention, nevertheless it will be understood that such are merely exemplary and that numerous modifications and rearrangements may be made therein without departing from the essence of the invention.

I claim:

1. In timing apparatus for governing the operation of a device at a preselected time, the combination of time-selecting means movable from a normal position to different time-selecting positions and operable to govern said device, time-driven means for driving said time-selecting means from said different time-selecting positions back to said normal position, mechanism for transmitting driving motion from said time-driven means to said time-selecting means comprising driving and driven members rotating on separate fixed axes and adapted to have direct driving engagement, and means for substantially interrupting said direct driving engagement when said time-selecting means has been restored to its normal position.

2. In timing apparatus for governing the

operation of a device at a preselected time, the combination of time-selecting means movable from a normal position to different time-selecting positions and operable to govern said device, time-driven means for driving said time-selecting means from said different time-selecting positions back to said normal position, mechanism for transmitting driving motion from said time-driven means to said time-selecting means comprising driving and driven members rotating about fixed axes and adapted to have peripheral driving engagement, and a clearance gap in the periphery of one of said members for substantially interrupting said driving engagement when said time-selecting means has been restored to its normal position.

3. In timing apparatus for governing the operation of a device at a preselected time, the combination of time-selecting means movable from a normal position to different time-selecting positions and operable to govern said device, continuously rotating time-driven means for driving said time-selecting means from said different time-selecting positions back to said normal position, mechanism for transmitting driving motion from said time-driven means to said time-selecting means comprising driving and driven wheels rotating about spaced fixed axes and adapted to have frictional driving engagement substantially at their peripheries, and a clearance pocket in said driven friction wheel for substantially interrupting said driving engagement when said time-selecting means has been restored to its normal position.

4. In an interval timer for governing the operation of a device after a selected time interval, the combination of time-selecting means manually settable from a normal position to different time-selecting positions and operable to govern said device, continuously rotating time-driven means for driving said time-selecting means from said different time-selecting positions back to said normal position, mechanism for transmitting driving motion from said time-driven means to said time-selecting means comprising driving and driven wheels rotating on separate fixed axes and adapted to have frictional driving engagement substantially at their peripheries for transmitting a speed reducing drive, one of said wheels comprising spring pressed gripping surfaces adapted to establish resilient frictional engagement with the other wheel, and a clearance pocket in said driven friction wheel in which said driving friction wheel is adapted to idle during the non-operating intervals of said timer, the driving engagement between said wheels being interrupted solely by said clearance pocket when said time-selecting means has been restored to its normal position.

5. In an interval timer, the combination of a time-selecting member, time driven means, and a driving connection therebetween comprising driving and driven friction wheels having peripheral driving engagement, one of said wheels comprising a pair of resilient discs, and the other of said wheels engaging between said discs and causing flexure of said resilient discs substantially at the point of peripheral engagement between said wheels.

6. In an interval timer, the combination of a manually actuated time selecting member, time driven means for driving the latter, and a driving connection therebetween comprising driving and driven friction wheels having peripheral

driving engagement, one of said wheels comprising a pair of resilient discs having abutting contact with each other substantially at their edges, and the other of said wheels having a wedge-shaped periphery producing a rolling spreading action between the peripheral edges of said resilient discs by outward flexure of the metal in said resilient discs substantially at the point of peripheral motion transmitting engagement between said wheels.

7. In an interval timer, the combination of a manually actuated time selecting member, time driven means for driving the latter back to a normal position, and a driving connection therebetween comprising driving and driven friction wheels rotating about fixed axes having peripheral driving engagement, one of said wheels comprising a pair of resilient discs, the other of said wheels engaging between said discs, and a clearance pocket in said driven wheel in which said driving wheel is adapted to idle during the non-operating intervals of said timer the driving engagement between said wheels being interrupted solely by said clearance pocket when said time selecting member has been restored to its normal position.

8. In an interval timer of the class described, the combination of a manually actuated time selecting member movable from a normal position to different time selecting positions, time driven means for driving said time selecting member back to said normal position, a driving connection between said time driven means and said time selecting member comprising driving and driven friction wheels adapted to have peripheral driving engagement, said driven friction wheel comprising a pair of resilient discs having abutting contact with each other substantially at their edges, said driving friction wheel comprising a wedge-shaped periphery having a rolling spreading action between the peripheral edges of said resilient discs, and a clearance gap cut out of the periphery of said driven wheel of sufficient size to receive said driving wheel and in which gap said driving wheel is enabled to rotate idly during the non-operating intervals of said timer, whereby the driving engagement between said wheels is interrupted when said time selecting member has been restored to its normal position.

9. In an interval timer, the combination of a manually settable member, time driven means, and a friction slippage connection therebetween comprising driving and driven friction wheels adapted to have peripheral driving engagement, a clearance gap in said driven wheel for interrupting the driving engagement between said wheels when said driven wheel is in a predetermined position, and a floating mounting for said driven wheel permitting the latter to wobble or adopt different axially inclined positions and different axially displaced positions in maintaining effective frictional engagement with said driving friction wheel.

10. In an interval timer, the combination of a manually settable member, time driven means, and a friction slippage connection therebetween comprising a driving friction wheel, a driven friction wheel comprising a pair of resilient friction discs between which said driving friction wheel is adapted to have peripheral driving engagement, and a floating mounting for said driven wheel comprising a driven shaft and a hub for said driven wheel capable of wobble motion on said driven shaft to enable said driven wheel to

adopt different axially inclined positions relatively to said driving wheel during the frictional driving engagement.

11. In combination, a driving friction wheel and a driven friction wheel rotating about substantially fixed axes and arranged for peripheral driving engagement, said driven friction wheel comprising a pair of aligned discs, said driving friction wheel having rolling frictional engagement between said discs, and a clearance gap in said driven wheel for interrupting the driving engagement between said wheels when said driven wheel is in a predetermined position, said driven friction wheel and clearance gap being so constructed as to enable said driving engagement to be reestablished by rotating said driven wheel relatively to said driving wheel.

12. In combination, a driving friction wheel and a driven friction wheel arranged for peripheral driving engagement, said driven friction wheel comprising a pair of cupped resilient discs mounted in opposed relation with their peripheral portions resiliently pressed together, said driving friction wheel comprising a wedge-shaped periphery having a rolling spreading action between said peripheral portions of the driven wheel and having line contact with each disc at the side edges of said wedge-shaped periphery, a floating mounting for said driven wheel enabling it to shift axially and to wobble laterally for maintaining accurate frictional engagement with said driving wheel, and a clearance gap cut out of the peripheral portions of said resilient discs in said driven wheel, said clearance gap being of larger radius than said driving wheel and automatically interrupting driving engagement between said wheels when said driven wheel is in a predetermined angular position.

13. In timing apparatus of the class described, the combination of a continuously rotating time-driven member, motion transmitting mechanism driven thereby comprising driving and driven wheels adapted to have cooperating engagement substantially at their peripheries, a clearance pocket in the periphery of said driven wheel for interrupting the drive to said driven wheel in one angular position of the latter, an adjustable arm adapted to have driving energy transmitted thereto from said time driven member through said motion transmitting mechanism, a stop, said driving energy tending to rotate said arm toward said stop and to maintain it in engagement therewith, means for manually adjusting said arm in a reverse direction to different positions away from said stop corresponding to different time intervals, a signal, a striker for said signal, means responsive to manual rotation of said adjustable arm in the manual setting operation for moving said striker to operative position, and means responsive to time driven rotation of said adjustable arm in the opposite direction for causing said striker to strike said signal.

14. In an interval timer of the class described, the combination of a continuously rotating time-driven member, motion transmitting mechanism driven thereby comprising driving and driven friction wheels adapted to have cooperating frictional engagement substantially at their peripheries, a clearance pocket in the periphery of said driven wheel for interrupting the drive to said driven wheel in one angular position of the latter, a tripping arm adapted to have driving energy transmitted thereto from said time driven member through said friction clutch, a stop, said driving energy tending to rotate said arm toward

said stop, said clearance pocket interrupting the drive to said driven wheel when said tripping arm is in engagement with said stop, means for manually adjusting said arm in a reverse direction to different positions away from said stop corresponding to different time intervals, a gong, a striker for said gong, a latch cooperating with said striker, means responsive to manual rotation of said tripping arm in the manual setting operation for moving said striker to cocked position, said latch thereupon holding said striker in cocked position, and means responsive to the time driven rotation of said tripping arm in the opposite direction for tripping said latch so as to cause said striker to strike said gong.

15. In an interval timer of the class described, the combination of an electric clock, a continuously rotating member driven by said clock at a timed rate, a friction clutch cooperating therewith, an adjustable tripping arm adapted to have driving energy transmitted thereto from said continuously rotating member through the medium of said friction clutch, a stop, said driving energy tending to rotate said arm toward said stop, means for manually adjusting said arm in a reverse direction to different positions away from said stop corresponding to different time intervals, a gong, a striker for said gong, a latch cooperating with said striker, means responsive to such manual rotation of said tripping arm in the manual setting operation for moving said striker to cocked position, means for causing said latch to thereupon hold said striker in cocked position, and means responsive to the time driven rotation of said tripping arm in the opposite direction for tripping said latch so as to cause said striker to strike said gong.

16. In an interval timer of the class described, the combination of a continuously rotating time driven member, a friction clutch, a tripping arm adapted to have driving energy transmitted thereto from said time driven member through said friction clutch, a stop, said driving energy tending to rotate said arm toward said stop, means for manually adjusting said arm in a reverse direction to different positions away from said stop corresponding to different time intervals, an operating member, contacts responsive to the actuation of said operating member to different positions, a latch for holding said operating member in one position, means responsive to such manual rotation of said tripping arm in the manual setting operation for moving said operating member to said latter position, and means responsive to the time driven rotation of said tripping arm in the opposite direction for tripping said latch so as to permit said operating member to move to another position.

17. In timing apparatus of the class described, the combination of a continuously rotating time-driven member, motion transmitting mechanism driven thereby comprising driving and driven wheels adapted to have cooperating engagement substantially at their peripheries, a clearance pocket in the periphery of said driven wheel for interrupting the drive to said driven wheel in one angular position of the latter, an adjustable arm adapted to have driving energy transmitted thereto from said time-driven member through said motion transmitting mechanism, a stop, said driving energy tending to rotate said arm toward said stop and to maintain it in engagement therewith, means for manually adjusting said arm in a reverse direction to different positions away from said stop corresponding

to different time intervals, signal means adapted to be operated by said arm when said arm is having driving energy transmitted thereto, means for confining the operation of said signal means to a relatively limited period of signaling.

18. In an interval timer of the class described, the combination of a continuously rotating time-driven member, motion transmitting mechanism driven thereby comprising driving and driven friction wheels adapted to have cooperating frictional engagement substantially at their peripheries, a clearance pocket in the periphery of said driven wheel for interrupting the drive to said driven wheel in one angular position of the latter, a tripping arm adapted to have driving energy transmitted thereto from said time-driven member through said friction clutch, a stop, said driving energy tending to rotate said arm toward said stop and to maintain it in engagement therewith, means for manually adjusting said arm in a reverse direction to different positions away from said stop corresponding to different time intervals, switch means, switch actuating mechanism comprising a lever operative to transmit motion from said tripping arm to said switch means, said switch actuating mechanism comprising means for preventing said switch means remaining in closed circuit position beyond a relatively limited period of time, and an audible signal device adapted to be controlled by said switch means.

19. In an interval timer of the class described, the combination of an electric clock, a continuously rotating member driven by said clock at a timed rate, a friction clutch cooperating therewith, said friction clutch comprising a driving and driven friction wheel adapted to have cooperating engagement substantially at their peripheries, said driven wheel having a clearance pocket therein at one point of its periphery for interrupting the drive to said driven wheel in one angular position of the latter, an adjustable tripping arm adapted to have driving energy transmitted thereto from said continuously rotating member through the medium of said friction clutch, a stop, said driving energy tending to rotate said arm toward said stop and tending to maintain it in engagement therewith, means for manually adjusting said arm in a reverse direction to different positions away from said stop corresponding to different time intervals, a lever spring-biased to neutral position and oscillatable in either direction from said neutral position, a pointed nose on said lever, a cooperating pointed nose on said adjustable tripping arm adapted to engage with the pointed nose on said lever for oscillating the latter, contacts responsive to said lever, and an audible signal device controlled by said contacts.

20. In timing apparatus of the class described, the combination of an electric clock, a continuously rotating member driven by said electric clock, a friction clutch cooperating therewith, said friction clutch comprising driving and driven wheels mounted on separate axes and adapted to have cooperating engagement substantially at their peripheries, means for automatically interrupting the drive between said wheels when said driven wheel is in the predetermined position, an adjustable tripping arm adapted to have driving energy transmitted thereto from said electric clock through said continuously rotating member and friction clutch, a stop, said driving energy tending to rotate said arm toward said stop and to maintain it in engagement therewith, means for manually adjusting said arm in a reverse

direction to different positions away from said stop corresponding to different time intervals, and signal means adapted to be operated by said arm for a brief time interval as said arm is rotating back into normal position against said stop. 5

21. In combination, a driving friction wheel and a driven friction wheel rotating about fixed axes and arranged for peripheral driving engagement, a clearance notch in the periphery of said driven wheel for interrupting the peripheral driving engagement between said wheels when said notch is in registration with the periphery of said driving wheel, and means for restoring the peripheral driving engagement between said wheels 10 by rotating said driven wheel relatively to said driving wheel while still maintaining the same fixed spacing between said wheel axes. 15

22. In combination, a first friction wheel and a second friction wheel rotating about fixed spaced axes and arranged for peripheral driving engagement, a clearance notch in the periphery of said second friction wheel for interrupting the peripheral driving engagement between said wheels when said notch is in registration with the periphery of said first friction wheel, and a lead-in surface at one end of said clearance notch for enabling the peripheral driving engagement between said wheels to be restored by rotating said second friction wheel relatively to said first friction wheel while still maintaining the same fixed spacing between said wheel axes, thereby revolving said clearance notch out of registration with the periphery of said first friction wheel.

WILLIAM P. GALLAGHER.
